CLAIM

We claim the ornamental design for an architectural panel with thin yarn interlayer, as shown and described.

DESCRIPTION

FIG. 1 is a front perspective view of an architectural panel with thin yarn interlayer, showing our new design.

FIG. 2 is a front view of the architectural panel with thin yarn interlayer.

FIG. 3 is a back view of the architectural panel with thin yarn interlayer.

FIG. 4 is a left side cross-section view of the architectural panel with thin yarn interlayer taken in the direction of line 4-4 of FIG. 2.

FIG. 5 is a right side cross-section view of the architectural panel with thin yarn interlayer taken in the direction of line 5-5 of FIG. 2.

FIG. 6 is a top cross-section view of the architectural panel with thin yarn interlayer taken in the direction of line 6-6 of FIG. 2; and,

FIG. 7 is a bottom cross-section view of the architectural panel with thin yarn interlayer taken in the direction of line 7-7 of FIG. 2.

The outer broken lines in FIG. 1 adjacent to the shaded portions of the design depict the bounds of the claim and all other broken lines depict environmental subject matter. All broken lines form no part of the claim.
